UNITED STATES PATENT OFFICE.

JAMES F. WILBUR, OF RICHFORD, NEW YORK.

WATER-TANK.

SPECIFICATION forming part of Letters Patent No. 340,532, dated April 20, 1886.

Application filed September 28, 1885. Serial No. 173,491. (No model.)

To all whom it may concern:

Be it known that I, JAMES F. WILBUR, a citizen of the United States, residing at Richford, in the county of Tioga and State of New York, have invented certain new and useful Improvements in Water-Tanks; and I do hereby declare the following to be a full, clear, and exact description of the invention, such as will enable others skilled in the art to which it appertains to make and use the same.

The object of this improvement is to provide a water tank with the parts of which it is composed formed and connected to each other in a manner adapted to give great strength to their jointure and great strength and durability to the whole structure. These results are attained by the construction illustrated in the drawings herewith filed as part hereof, in which the same letters of reference denote the same parts in the different views.

Figure 1 is a plan view of a water-tank embodying the features of my improvement. Fig. 2 is a side elevation of the same. Fig. 3 is a plan view of a modification. Fig. 4 is a side elevation of the same. Fig. 5 is a representation of a segment of the modified structure. Fig. 6 is a representation of a segment having a formation adapted to the octagonal structure shown in Figs. 1 and 2, and provided with dotted curve-lines for the purpose of more fully illustrating the practicability of the modification shown in Figs. 3 and 4. Fig. 7 is a sectional representation of the construction shown in Figs. 1 and 2, and provided with dotted curve lines for the purpose of more fully demonstrating the practicability of the modification illustrated in Figs. 3 and 4. Fig. 8 is a representation of a segment of the octagonal structure. Fig. 9 is a view illustrating the practicability of making the structure cylindrical inside and octagonal outside by cutting away the inside edges of the segments of the octagonal structure at suitable curves, and thereby more fully illustrating the practicability of the modification shown in Figs. 3 and 4.

Referring to Figs. 1 and 2, A is the bottom of the tank, which is to be set upon a suitable supporting-frame.

B B and C C represent series of segments

forming the tank-wall. These segments are made from strips of plank, preferably two inches thick by four inches wide, and provided with transversely-beveled ends b b', inclined toward each other; or, in other words, so beveled that the segments may be set together in the order shown, with one end of each segment against the inside edge, b², of the adjoining segment. The segments C C are of exactly the same construction, but have one of their ends set against the inside edge of the adjoining segments in reverse order or direction to that of the segments B B. The lower series of segments are suitably secured to the bottom A, and the several series of segments are secured to each other by spikes or screws, as shown at D. The segments may be made curved intermediate of their ends, and the structure made cylindrical in form, if desired, which is the object of the modification shown in Figs. 3 and 4, in which A is the bottom.

B' B' are segments having their outside edges curved their entire length and part of their inside edges curved and the remaining part straight, as shown at b³ b⁴ in Figs. 3 and 5, and having one end, b⁵, beveled at exactly the same angle as the corresponding ends of the segments in the octagonal structure, as more fully shown in Figs. 6, 7, 8, and 9, so that they may be set together in the order shown, with one end of each segment against the inside or straight edges of the adjoining segments.

C' C' are segments of exactly the same construction as the segments B', but have their beveled ends set against the inside or straight edges of the adjoining segments in reverse order or direction to that of the segments B'. The lower segments, C', are secured to the bottom A, and the several series of segments are secured to each other by spikes or screws D, as in the octagonal structure.

Referring to Fig. 6, B represents a piece of plank having straight and parallel edges and its ends cut away at angles, adapting the same to forming a segment of an octagonal structure substantially as shown in Figs. 1 and 2, and, as indicated by the adjacent dotted lines, agreeing with the profile of the piece B and that of an octagonal structure. By cutting away the body of the piece outside of the dotted lines,

ted curve-lines within the same the piece would form the counterpart to the segments B', (shown in Figs. 3 and 5,) and a number of such segments would therefore go together in the order shown in Figs. 1 and 2, and form a cylindrical structure, as shown in Figs. 3 and 4.

Referring to Fig. 7, B B B represent segments of an octagonal tank set together substantially in the order stated. By observing the dotted lines in this figure it will be obvious that by giving the segments suitable curves the parts may be set together in the order shown in Figs. 1 and 2, and made to form a cylindrical structure.

15 By cutting away the inside edge, b^2 , of the octagonal segment B, (shown in Fig. 8,) and curving the same as shown at b^3 in Fig. 9, the segments could be set together in the order shown in Figs. 1 and 2, and made to form a structure with a cylindrical inside and an octagonal outside, as indicated by the dotted lines in Fig. 9, which still more abundantly elucidates the practicability of the modification set forth.

20 The special purpose and features of the improvement is not a structure of either octagonal, cylindrical, or other particular form, but a structure of great strength, which is attained by the peculiar manner in which the parts are set together and the reverse order in which the alternate series of segments are set together, and thereby making each of series of segments lap and strengthen the jointures of their adjacent series.

The octagonal structure shown in Figs. 1 and 2 can be made at less expense than a cylindrical structure of substantially the same dimensions, as there would be no material waste of lumber in forming the parts. The cylindrical structure would be more expensive, for the reason that the lumber would cut to waste in forming the parts, but the additional expense would be compensated by the increased inside area of the cylindrical structure, as indicated by the dotted lines in Figs. 6, 7, and 9.

25 Either the octagonal or cylindrical structure herein described is adapted for and could be used as a bin.

Having explained the features of my improvement, what I claim as new, and desire to secure by Letters Patent, is—

30 A tank constructed, as herein shown and described, of segments arranged with their ends and inner edges set alternately against the ends and inner edges of their adjoining segments, each horizontal series of segments having the same formation and being arranged in reverse order to its vertically-adjacent series in order that each alternate series of segments may strengthen the joints of the adjacent series, all secured together by spikes or screws, as and for the purpose set forth.

35 In testimony whereof I affix my signature in presence of two witnesses.

JAMES F. WILBUR.
